(57) **CLAIM**

We claim the ornamental design for a kite reel, as shown and described.

DESCRIPTION

FIG. 1 is a perspective view of the kite reel design; FIG. 2 is a rear elevational view thereof, the front being a mirror image thereto;

FIG. 3 is a front plan view thereof;

FIG. 4 is a bottom view thereof;

FIG. 5 is a right side elevational view thereof; and,

FIG. 6 is a left side elevational view thereof.
